Dispensers, Inc., Santa Barbara, Calif., a corporation
of California

Filed Feb. 14, 1966, Ser. No. 1,035

Term of patent 14 years

(Cl. D44—21)

FIG. 4

FIG. 5

FIG. 1 is a perspective view of a pitcher or similar article showing my new design;

FIG. 2 is a top plan view thereof taken along line 2-2 of FIG. 3;

FIG. 3 is a side elevational view thereof;

FIG. 4 is a perspective view of a pitcher or similar article showing another form of my new design wherein the height is diminished and the diameter is increased;

FIG. 5 is a top plan view thereof taken along line 5-5 of FIG. 6; and

FIG. 6 is a side elevational view thereof.

The characteristic features of my design reside in the particularly shaped handle member, cover and knob, and pouring spout in combination with the body of the configuration shown.

I claim:

The ornamental design for a pitcher or similar article, substantially as shown and described.
